(57) **CLAIM**

The ornamental design for a bathtub brush, as shown and described.

DESCRIPTION

FIG. 1 is a front, right, and top perspective view of a bathtub brush, showing my new design assembled;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion "9" shown in FIG. 1;

FIG. 10 is an enlarged view of portion "10" shown in FIG. 1;

FIG. 11 is an enlarged view of portion "11" shown in FIG. 2;

FIG. 12 is an enlarged view of portion "12" shown in FIG. 2;

FIG. 13 is a rear, left, bottom perspective view, shown disassembled to show portions of the design not clearly visible when combined; and,

FIG. 14 is an enlarged view of portion "14" shown in FIG. 13.

The dash-dash broken lines shown in the drawings illustrate portions of the bathtub brush, and forms no part of the claimed design. The dot-dash broken lines seen in FIGS. 1, 2, 9, 10, 11, 12, 13, and 14 depict enlarged view indicators, and forms no part of the claimed design.

1 Claim, 14 Drawing Sheets
